[57] CLAIM

The ornamental design for a combined scuba repair kit case and can holder, as shown and described.

DESCRIPTION

FIG. 1 is a front perspective view of a combined scuba repair kit case and can holder showing my new design; FIG. 2 is a bottom plan view thereof;

FIG. 3 is a fragmentary view of the lid of FIG. 1 with the pouch in a folded position;

FIG. 4 is a rear perspective view of the case of FIG. 1 with portions of its side wall broken away for illustrative purposes;

FIG. 5 is a front perspective view of the case of FIG. 1, closed and showing the can holder above;

FIG. 6 is a rear perspective view of the case of FIG. 5, closed;

FIG. 7 is a fragmentary view of the top portion of FIG. 5 with the can holder removed; and,

FIG. 8 is a bottom perspective view of the can holder, removed from the case of FIG. 5.

FIG. 1

FIG. 2

FIG. 3

FIG. 4
